A handwritten signature in black ink, appearing to read "Fred. W. Teetzel".

Attorney.

UNITED STATES PATENT OFFICE.

FRED W. TEETZEL, OF LOS ANGELES, CALIFORNIA.

DESIGN FOR A CARTON.

Application filed December 27, 1927. Serial No. 24,661. Term of patent 3½ years.

To all whom it may concern:

Be it known that I, FRED W. TEETZEL, a citizen of the United States, residing at Los Angeles, in the county of Los Angeles, State of California, have invented a new, original, and ornamental Design for a Carton, of which the following is a specification, reference being had to the accompanying drawing, forming a part thereof.

Fig. 1 is a front view of a carton showing my new design;

Fig. 2 is a side view of a carton showing my new design; and

Fig. 3 is a rear view of a carton showing my new design.

I claim:

The ornamental design for a carton, as shown.

FRED W. TEETZEL.
